LEG EXERCISING MACHINE

George B. Ritter, Fort Worth, Tex.

Application November 19, 1954, Serial No. 33,170

Term of patent 3½ years

(Cl. D83—1)

Figure 1 is a perspective view of a leg exercising machine embodying my new design.

Figures 2, 3 and 4 are, respectively, a side elevation and end views of the machine shown in Figure 1.

I claim:

The ornamental design for a leg exercising machine, substantially as shown.
